CLAIM

The ornamental design for an automated slide stainer, as shown and described.

DESCRIPTION

FIG. 1 is a left-top-front perspective view of a first embodiment of an automated slide stainer, showing our new design; FIG. 2 is a front elevation view thereof; FIG. 3 is a rear elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a left-top-front perspective view of a second embodiment of an automated slide stainer; FIG. 9 is a front elevation view thereof; FIG. 10 is a rear elevation view thereof; FIG. 11 is a right side elevation view thereof; FIG. 12 is a left side elevation view thereof; FIG. 13 is a top plan view thereof; and, FIG. 14 is a bottom plan view thereof.

The broken lines in the figures depict portions of the automated slide stainer that form no part of the claimed design. The grayed areas depict a color contrast, and does not represent any particular color, materials, texture, or finish.
